J. STRASZER.

Wick-Raisers.

No. 141,673.

Patented August 12, 1873.

ATTEST:

Robert Burns.

INVENTOR:

John Straszer
By Knight, Ward & Atty.

UNITED STATES PATENT OFFICE.

JOHN STRASZER, OF ST. LOUIS, MISSOURI.

IMPROVEMENT IN WICK-RAISERS.

Specification forming part of Letters Patent No. **141,673**, dated August 12, 1873; application filed June 30, 1873.

To all whom it may concern:

Be it known that I, JOHN STRASZER, of St. Louis, St. Louis county, Missouri, have invented an Improvement in Lamp-Burners, of which the following is a specification:

This invention consists in the provision of a collar having one or more spiral projecting ribs or flanges, which act directly on the wick to elevate or depress the same as the collar is turned. This invention also consists in forming the collar of suitable spring metal and slotting it so that the part or parts that are screw-threaded or carry the spiral rib or ribs will form spring sections, which constantly tend to keep their spiral ribs or screw-threads embedded in the wick, and so that the spiral ribs will be accommodated to the size of the wick.

Figure 1 is a perspective view, showing my improvement applied to a locomotive head-light burner, the wick-operating collar being raised out of place to show its construction. Fig. 2 is an axial section, showing the parts in position. Fig. 3 is an under perspective view, showing my improvement applied to the common Argand burner. Fig. 4 is a perspective view of a modification of the wick-operating collar of the head-light burner.

A is the outer, and B the inner barrel of the body of the burner, and forming with the bottom C an annular chamber for the wick and oil, and which is connected to the oil-reservoir by the usual neck a. D is a drip-pan, arranged below the burner, having perforations d in the sides or top to allow the passage of air through the interior of the barrel B. The collar by which the vertical adjustment of the wick is made is formed of two concentric rings, E F, united at the top. This collar fits on the top of the barrel B, and may be turned freely thereon. The inner ring F is connected by arms f to the collar G, in which is fixed the vertical rod H, that passes through the burner and through an incasing-sleeve, D', secured to the bottom of the drip-pan D, and is provided with an operating hand-wheel, I, and nut i, which screws on the rod and holds the parts to-

gether. The rod H at its upper end carries the adjustable deflector K. The outer ring E of the collar is slotted so as to form any required number of spring sections or wings, e, (four of which are shown in Figs. 1 and 3, and two in Fig. 4,) and which are formed with spiral projecting ribs or flanges e', which are forced out to embed themselves in the wick L by the spring of the sections e.

In Fig. 1 the spring sections e are united at their middle to the rim E by the connection-pieces e'', and are disconnected from each other by vertical slots, so as to have an outward spring at each end, while in Fig. 4 the two sections e are connected to the main part E by one vertical connecting-piece, e'', so that there are only two spring-wings, carrying spiral flanges, in this form.

In the modification shown in Fig. 3, the adjusting-collar E is placed outside of the wick, and its flanges e' are turned inward. Its upper edge is turned outward, and serves as a means for its rotation. It is formed similarly to the collar before described, except that the inner annular part F is omitted and the spiral ribs e' project inward instead of outward.

My improvement may be modified by forming or securing the spring sections e with their spiral ribs e' on the barrel in contact with one side of the wick, and forming the collar on the other side of the wick with vertical ribs, so that as the wick is turned with the collar the stationary spiral ribs shall act upon it to elevate or depress it.

I claim—

1. The collar E F, provided with spring sections or wings e, having spiral ribs or flanges e', which act directly on the wick, substantially as set forth.
2. The combination of the collar E F, wings e, and spiral ribs e' with the barrels A B, collar G, arms f, and rod H, as and for the purpose set forth.

JOHN STRASZER.
